FARADAY SHIELD SUPPRESSOR FOR SECONDARY EMISSION CURRENT IN CROSSED ELECTRIC AND MAGNETIC FIELD ELECTRONIC TUBES

John H. Goncz, Waltham, Mass., assignor to Edgerton, Germeshausen & Grier, Inc., Boston, Mass., a corporation of Massachusetts

Filed Jan. 9, 1962, Ser. No. 165,195
4 Claims. (Cl. 313—106)

This invention relates to a method and a device for controlling the secondary electron emission in electron tubes where primary electrons are directed toward and impinge upon an electrode, and more particularly for suppressing secondary electron emission from an electrode of tubes in which the electron flow is subjected to crossed electric and magnetic fields.

Secondary electron emission from an electrode such as the anode represents a substantial energy loss in an electron tube and it is particularly serious in tubes having crossed electric and magnetic fields which cause the electrons to flow in a cycloidal path. Prior solutions to this problem have included (1) carbonizing the anode, (2) placing a suppressor grid of negative polarity with respect to the anode in the vicinity of the anode electrode, and (3) forming the anode of an irregular shape to trap secondary electrons that are produced. Each of these solutions possess certain disadvantages not found in the present invention.

In carbonizing the anode, or applying a plurality of black layers thereto, the electrons are trapped in a labyrinth of small particles. This method, however, is only successful in reducing secondary emission to about 50% of the number of primary electrons striking the anode. It is a serious disadvantage of this method that it is only 50% effective.

By placing a suppressor grid having a negative potential with respect to the anode adjacent to the anode, secondary emission is substantially reduced over carbonized anodes but undesirable currents are induced in the anode by the motion of the electrons in the electric field between the two electrodes. These currents cause an energy loss which neutralizes the gain obtained by the reduction of secondary emission. Furthermore, a time smear, or loss of high frequency response is brought about by the motion of the electrons.

The third method which has been employed in the prior art, is shaping the anode electrode to such a configuration that it has a series of depressions so disposed that the secondary electrons, emitted upon the impingement of the primary electrons, also strike a portion of the anode emitting tertiary electrons. Due to the reduced energy of the secondary electrons over that of the primary electrons, and the reduced energy of the tertiary electrons over the secondary, the secondary, tertiary and further orders of electrons are trapped and prevented from leaving the anode. This system has greatly reduced energy loss but to accomplish this end, a complicated and expensive anode configuration is required which greatly increases the cost of producing such a device. Furthermore, such configurations still possess areas from which secondary emission takes place since the flow of primary electrons cannot be so controlled that they strike the most advantageous points on the anode surface.

It is an object of this invention to provide an electrode structure which will control the secondary electron emission from the electrode to greatly reduce energy losses therefrom without the above-mentioned disadvantages.

Another object of this invention is to provide a simple inexpensive anode structure that will greatly reduce energy losses due to secondary emission from the anode.

A further object of this invention is to provide a new

and novel method of reducing energy losses caused by secondary electron emission from an electrode.

In summary, this invention consists of making the space immediately in front of an electrode free of electric fields while not affecting any magnetic fields that may be present. The electric field-free space extends a distance normal to the electrode which is less than the radius of the circular path described by the primary electrons in the existing magnetic field but greater than the radius of the circular path of the secondary electrons. One device for carrying out this method is a magnetic Faraday cage or shield spaced the above-defined distance from the electrode and energized to the same potential as the electrode.

Faraday cages have been used very successfully in electrostatic fields as efficient collectors of electrons. By this invention, it is used for the first time in a magnetic field, and an efficient, simple and inexpensive suppressor of secondary electron emission losses is produced thereby.

Other and further objects of this invention will be more particularly pointed out in the following description and in the appended claims.

The invention will now be described in connection with the accompanying drawing in which:

FIGURE 1 is a schematic view of an electron tube embodying the subject invention;

FIGURE 2 is an end view of the tube of FIGURE 1;

FIGURE 3 is an explanatory diagrammatic view of the anode electrode area of an electron tube; and

FIGURE 4 is a view similar to that of FIGURE 3 but also including the magnetic Faraday cage.

The tube shown in FIGURE 1 is an amplifier tube having crossed electric and magnetic fields. This tube has within its envelope 1, a cathode 2, a control grid 3, a series of secondary electron emitting dynodes 4, 5 and 6, an anode 7, a Faraday cage 8 and a high-voltage rail 9. The cathode 2 is connected to the grounded side of a high voltage supply shown as battery B. The input signal is fed to the control grid 3 which causes the flow of electrons from the cathode 2 to dynode 4 which acts as a plate for the triode section of the tube. The electron flow is caused to follow a cycloidal path due to the combined effect of crossed magnetic and electric fields. The magnetic field in the path of the electron flow is produced by a pair of magnets N and S externally mounted adjacent to the tube envelope 1 as shown in FIGURE 2. The electric field is produced by the high-voltage rail 9 connected to battery B₁. These two fields, the magnetic field produced by the magnets N and S, and the electric field produced by the high-voltage rail 9, are mutually perpendicular and combine to cause the electrons to flow in a cycloidal path from the cathode 2 to the dynode 4. Each of the dynodes 4, 5 and 6 have a secondary-electron emitting surface such as, for example, magnesium oxide, in order to multiply the electrons by emitting a plurality of secondary electrons for each primary electron striking the dynode. The electrons emitted by dynode 4 follow a cycloidal path to dynode 5 where an increased number of electrons are emitted which flow to dynode 6 where the multiplying effect again takes place causing the electrons to flow to the anode 7. The anode 7 is connected to the high-voltage side of the battery B. Each of the dynodes 4, 5 and 6 and the anode 7 are held at progressively higher potentials by the voltage divider R₁, R₂, R₃ and R₄ connected between the grounded cathode 2 and the anode 7.

Referring now to FIGURE 3, the anode 7 is a smooth planar electrode of a conducting metal such as, for example, copper or the like. It is important to reduce secondary emission from the anode 7 to as low a level as possible to prevent energy loss and to realize in the output as much of the amplification produced within the tube as possible. This may be accomplished by making the space

in front of the anode 7 free of electric fields and particularly the electric field produced by the high-voltage rail 9 previously described. This space resides within the dotted lines shown in FIGURE 3. Electrons moving from dynode 6 toward the anode 7 follow a cycloidal path in response to the combined effect of the crossed magnetic and electric fields. Once an electron enters the electric field-free space, it is subject only to the magnetic field produced by magnets N and S and, therefore, the path of the electron becomes circular. If the height d of this electric-field-free space extending normal to anode surface is greater than the radius of the circular path the electron follows in this space, the electron will not reach the anode but will, following the circular path, pass a distance above the anode and head out away from the anode. It is, therefore, an important consideration that the distance d , defining the outer limit of this space be less than the radius of the circular path that the electron follows in the electric field-free space.

The radius of the circular path of the electron is a function of the voltage of the electron and the strength of the magnetic field both of which may be calculated for the particular tube application. By making the distance d less than the radius of the circular path of the electron, the electron is assured of striking the anode surface.

Upon the impingement of the electron on the anode surface, a secondary electron is emitted therefrom. The secondary electron has considerably less energy than the primary electron which liberated it, usually less than 10% of the energy of the primary electron. By virtue of its energy at liberation, the secondary electron will move away from the anode surface and follow a circular path under the control of the magnetic field within the said space. The radius of the secondary electron's circular path will be considerably smaller than that of the primary electron due to its much lower voltage.

If the distance d is less than the radius of the circular path of the secondary electron, it will pass outside the electric field-free space where it will be subject to both the magnetic field and the electric field and its circular path will become a cycloidal path which can cause it to move out of the anode area. If, however, the distance d is made greater than the radius of the circular path of the secondary electron, there is no chance that the secondary electron may pass outside the said space and since it will follow a circular path, it must return to the anode, thus insuring no loss of energy.

It can be seen from the foregoing that for maximum efficiency, the distance d must be less than the radius of the circular path of the primary electrons and greater than that of the circular path of the secondary electrons.

FIGURE 4 shows a Faraday cage 8 disposed a distance d from the anode 7. The cage 8 consists of a rectangular grid energized to the same potential as the anode as shown by conductor 10, FIGURE 1. The cage 8 is shown to be substantially the same size as the anode surface and disposed parallel thereto. This is not the only configuration that may be used. It only represents a preferred embodiment. The cage 8 may be considerably larger than the anode or it may be slightly smaller. It need not be parallel to the anode surface as long as maximum and minimum distances d , measured normal to the anode surface are within the above-mentioned limits.

By energizing the cage 8 and the anode 7 to the same potential the space therebetween is made substantially free of electric fields, thereby leaving only the magnetic field in this area. The electric field above the surface of the grid will not be completely shielded by the cage 8 but it will penetrate into the cage area to some slight degree. In my experiments, I have found that the percentage of

penetration is inversely proportional to the distance d , reaching a maximum of less than 5% for the smallest useable d .

The efficiency of the magnetic Faraday cage is measured not in terms of the number of secondary electrons which fail to return to the anode because this is substantially nil, but, rather, in terms of the geometrical transmission of the cage. This is simply the ratio of open space in the cage grid to the total area of the cage grid. Fine mesh grids are commercially available with geometrical transmission in excess of 85%. This means that more than 85% of the primary electrons reaching the cage pass through it and strike the anode while less than 15% impinge upon the cage grid and are lost.

FIGURE 4 is similar to FIGURE 3 except that the Faraday cage grid is disposed at the outer edge of the electric field-free space. A primary electron is shown in a cycloidal path before it passes through the cage grid 8 where its path changes to a circular path before it strikes the anode 7 causing a secondary electron to be liberated which moves in a circular path completely within the said space and then strikes the anode. If the secondary electron liberates a tertiary electron when it strikes the anode, the energy of the tertiary electron would be so small that its circular path would have an extremely small radius.

As an example, I have tested my invention in an amplifier tube with a magnetic field of 522 gauss and an electric field of 7.68 kv./cm. The primary electrons entered the cage grid with energies of 450 volts where they entered circular paths having a radius of 0.053 inch. Most of the secondary electrons had energies less than 20 volts, but using an upper limit of 50 volts, the radius of its circular path was 0.018 inch. Thus, distance d must be between 0.018 and 0.053 inch. The d actually used was 0.037 inch, substantially, the mean distance.

Other and further modifications will occur to those skilled in the art and all such are considered to fall within the spirit and scope of the invention, as defined in the appended claims.

I claim:

1. In an electron stream apparatus in which the electron stream flow is under the control of crossed electric and magnetic fields, a secondary electron emission controlling device comprising: a pair of substantially parallel planar electrodes including a collector toward which the stream of primary electrons is directed and a grid disposed a predetermined distance from the said collector in the path of the said electron stream; and means for energizing said collector and said grid to substantially the same potential, said predetermined distance being intermediate the radius of the circular path of the primary electrons when subjected to only the magnetic field, and the radius of the circular path of secondary electrons liberated by the impingement of primary electrons on the said electrode when said secondary electrons are subject to magnetic field only.

2. A device as claimed in claim 1 and in which the said collector and the said grid are coextensive.

3. A device as claimed in claim 1, in which said grid has a greater open area than closed area.

4. A device as claimed in claim 1 in which said grid electrode has a rectangular grid.
